(57) **CLAIM**

The ornamental design for a time switch, as shown and described.

DESCRIPTION

FIG. 1 is a perspective view of a time switch showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of another state of the time switch thereof.

The broken lines shown in the drawings depict portions of the time switch that form no part of the claimed design.

1 Claim, 8 Drawing Sheets
